Primary Examiner — Jennifer Rivard

Assistant Examiner — Alison M Ofstun

(57) **CLAIM**

The ornamental design for a comb part, as shown and described.

DESCRIPTION

FIG. 1 is a front view of a comb part showing my new design;

FIG. 2 is a back view thereof;

FIG. 3 is a right-side view thereof;

FIG. 4 is a left-side view thereof;

FIG. 5 is a top plan view thereof;

FIG. 6 is a bottom plan view thereof; and,

FIG. 7 is a rear top left perspective view thereof.

The broken lines depict portions of the article that form no part of the claimed design.
